UNITED STATES PATENT OFFICE.

HART D. NEWMAN, OF NEW ORLEANS, LOUISIANA.

DESIGN FOR A THERMOS BOTTLE.

60,566.

Specification for Design.

Patented Mar. 7, 1922.

Application filed December 27, 1919. Serial No. 348,192. Term of patent 3½ years.

To all whom it may concern:

Be it known that I, HART D. NEWMAN, a citizen of the United States, residing at New Orleans, in the parish of Orleans and State of Louisiana, have invented a new, original, and ornamental Design for a Thermos Bottle, of which the following is a specification, reference being had to the accompanying drawing, forming part thereof.

The figure is an elevation of a thermos bottle showing my new design.

I claim:

The ornamental design for a thermos bottle, as shown.

HART D. NEWMAN.
